UNITED STATES PATENT OFFICE.

DAVID S. GUENTHER, OF DAYTON, OHIO.

WALL-BRACKET FOR SUPPORTING FIRE-EXTINGUISHERS.

1,226,068.

Specification of Letters Patent. Patented May 22, 1917.

Application filed May 4, 1916. Serial No. 95,309.

To all whom it may concern:

Be it known that I, DAVID S. GUENTHER, a citizen of the United States, residing at Dayton, in the county of Montgomery and State of Ohio, have invented certain new and useful Improvements in Wall-Brackets for Supporting Fire-Extinguishers; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in brackets or holders for fire extinguishers. The object of the invention is to provide a device of this type which securely holds the fire extinguisher in a convenient manner and from which position it may be conveniently removed. A further object of the invention is to provide a bracket or support which is adapted to hold the fire extinguisher or container firmly so that it is immovable while supported thereon, and yet the container or casing will not be indented or marred.

In the accompanying drawings, Figure 1 is a front elevation of my improved bracket or support showing a fire extinguisher held thereon, the bottom cup of the bracket being shown in section; Fig. 2 is a side elevation of the bracket supporting the fire extinguisher; Fig. 3 is a cross-section on the line *a—a* of Fig. 1; Fig. 4 is a detail view showing the inner side of one part of the clamping band; Fig. 5 is a view of the T-bolt removed.

In a detail description of the invention, similar reference characters indicate the same parts.

The bracket consists of a narrow back plate 1 which is attachable to a wall or other convenient place of support by means of screws 2—2 at each end. A rib 3 extends outwardly from the longitudinal center of the back plate 1 and at the bottom thereof said rib terminates in a cup 4 having a central opening 5. The upper or concaved side of the cup 4 is lined with felt or other comparatively soft material 4' to protect the container 8 when supported thereon. The upper portion of the bracket supports a clamping band or ring one-half of which, to wit, 6, is rigid or an integral part of the

bracket, and the other half of which, to wit, 7, is hinged at 22 and may be swung upon its hinge to receive the body of the fire extinguishing shell 8. The free ends 9 and 10 of both band members 6 and 7 extend out and come together when the band is closed around the shell 8. As is shown more clearly in Fig. 4, both ends 9 and 10 have openings 11 which register with each other when the ends are brought together, also openings 12, which align in the same way. The ends 9 of the fixed band member 6, in addition to its opening 11 has a transverse recess 13, shown best in Fig. 4 in broken lines. A bolt 14 having a cross pin 15 on its end thereof, is supported in the hinged band member 7 and by turning it so the cross pin 15 comes to a position parallel and in line with the openings 11, the pin 15 may be projected through both openings 11 and turned to bring it crosswise in the recess 13 and thereby clamp both band members around the container. A similar movement of the bolt 14 to bring the cross pin 15 in alignment with the openings 11 enables a spring 16 to withdraw the pin 15 from the opening 11 in the fixed band member 6 and the band member 7 may be swung on its hinge to remove the container 8. The coil spring 16 incloses the bolt 14 and is confined between the end 10 of the movable band member 7 and the head or handle portion 17 of the bolt. As shown in Fig. 4, the inner sides of the clamp or band members 6 and 7 are provided with inlaid felt 18 which engages the shell 8 and holds the same, firmly without indenting or marring it. From the top of the bracket an overhanging arm 19 extends and engages the handle portion 20 of the shell 8 and prevents an upward withdrawal of the same while the clamp or band members 6 and 7 are closed. The lower end of the shell 8 has a nipple or projection 21 which fits into the central opening 5 of the cup 4. An ordinary padlock (not shown) may be employed in connection with the openings 12 to prevent opening of the clamp or band members where the fire extinguisher is mounted in places requiring this precaution. Otherwise, the T-pin or bolt 14 is an efficient means for locking the bands 6 and 7 to prevent unnecessary removal of the container 8.

Having described my invention, I claim:

1. A bracket for the purpose specified, comprising a back plate having a cup-shaped supporting part at one end adapted

- to receive the lower end of a hand fire extinguisher, a two-part clamp on the upper part of said plate one member of which is hinged, a bolt one end of which terminates in a cross pin and the other end in a handle, the cross arm being adapted to lock the clamp and to release it, and a spring on said bolt controlling the clamp when in a locked position.
- 10 2. A bracket, comprising a back plate having a supporting cup on its lower end and an arm extending from its upper end, a clamp consisting of two members one member being fixed to the upper part of said

bracket and the other member being hinged 15 to the fixed member, said clamp members having their free ends extended parallel with each other and provided with registering apertures, one of said clamp members having a transverse surface recess crossing 20 the aperture therein, and a spring-pressed T-bolt penetrating the apertures in said clamp extensions and coöperating with the apertures and recess therem in securing said clamp members and in releasing them. 25

In testimony whereof I affix my signature.

DAVID S. GUENTHER.
